UNITED STATES PATENT OFFICE.

GEORG VON ARCO, OF BERLIN, GERMANY, ASSIGNOR TO GESELLSCHAFT FÜR DRAHTLOSE TELEGRAPHIE M. B. H. HALLESCHES UFER 12/13, BERLIN, GERMANY, A CORPORATION OF GERMANY.

APPARATUS FOR THE GENERATION OF SHORT ELECTRICAL WAVES.

Application filed July 15, 1925, Serial No. 43,771, and in Germany July 25, 1924.

It is well known that an oscillation circuit may be produced by subjecting the charge supplied from a high tension direct current source to the control of a rapidly running interrupter. Of course, this method will prove unsuccessful in cases in which frequencies are used of such a high value as have of late come into practice for the purpose of bridging very great distances in radio work, i. e., ranging up to 10-30 million oscillations per second.

According to this invention, iron core coils are used for the object of interrupting the supply current whereby very high modulated or chopped waves are obtained.

Iron containing coils have become known in high frequency equipments for the purpose of control under the name of chopper or modulator chokes or coils. By the variation of a direct current auxiliary magnetization, the inductance and consequently the alternating current resistance of the coils is varied, and in this regard they behave just like modulator coils.

Measurements have shown that these coils vary in their behavior if the frequency becomes very high. On account of the higher losses in the iron, within the range of frequencies here under consideration, they do not behave like variable self inductances, but like variable ohmic resistances. It is comparatively easy to make coils which vary their resistance at the ratio of 1:20 or even as 1:30 if they are provided with auxiliary direct current magnetization.

Now, this characteristic is used in the present invention where the coil is inserted as an interrupter between the oscillatory circuit and the high tension source.

In the diagrammatic drawing herewith forming part of the specification, a form of construction is shown by way of example embodying this feature. *a* is the oscillatory circuit which is fed with direct current by way of the terminals *b*; *c* is the modulator coil whose auxiliary magnetizing winding *d*, is supplied by oscillator *e* with a current of high frequency, instead of with direct current or low frequency alternating current. This current may be generated, for instance, by means of a separate tube generator. The controlling current has such a frequency that

either for each oscillation of the high frequency working circuit *a* or a whole multiple thereof, a charge impulse is supplied. 55

In an arrangement of this sort, the shape of the voltage curve of the current with which the modulator coil is magnetized, is of utmost importance. The current curve must be of such a form that the magnetizing curve attains its crest value as rapidly as feasible, that it preserves this value for a short while, and that it is thereupon caused to drop as steeply as possible. Until the next rise takes place, there should be a time 65 interval three times as long during which the working circuit goes through $\frac{3}{4}$ oscillation. In order to produce a magnetizing current of such a nature, because of the great oscillation constancy required, the 70 most convenient plan is to use a cathode tube generator in which, by the adoption of suitable means, for instance, by the aid of iron core coils, such a distortion as stated is obtained in the current or the voltage 75 curve. It is only if this magnetization is made to operate with absolute uniformity and regularity that a constant current amplitude is realized in the high frequency circuit. The magnetization therefore, is at the 80 same time a measure and criterion of the constancy and regularity of the exciter. Instead of providing a charge impulse for each whole oscillation of the working circuit, it may be sufficient to give a charge 85 impulse for every two, three, or more whole oscillations of the working circuit, similarly as done in shock-excitation. In other words, the excitation is in rhythm with the oscillation circuit. Until the next energy supply 90 occurs, the amplitude of the working circuit falls off.

Instead of using a cathode tube for the control of the choke it would also be possible, at least for the case where a new charge 95 impulse is to be produced for each oscillation of the high frequency circuit, to take the control energy also from the high frequency circuit itself. In this case it must, of course, be kept in mind that, apart from 100 the proper voltage and current curve, the position of the phase of the magnetizing current must be in the proper relationship to the phase of the high frequency circuit.

What I claim and desire to protect by Letters Patent is:

1. In an apparatus for producing short electrical waves, an oscillation circuit supplied with energy from a high tension direct current source and an iron core choke coil in series with said circuit and excited at a predetermined high frequency differing from the frequency of the high frequency current in the oscillation circuit.
2. In an apparatus for producing short electrical waves, a high frequency oscillation circuit supplied with energy from a high tension source and an iron core choke coil excited by a high frequency current having a predetermined frequency and phase with respect thereto the excitation frequency differing from that of the resonant frequency of the oscillation circuit.
3. In apparatus for generating high frequency electrical oscillations, an oscillation circuit, a high tension direct current source and an iron cored choke coil in series, and a high frequency oscillator exciting said choke coil at a frequency equal to a fraction of the resonant frequency of said oscillation circuit.
4. In apparatus for shock exciting a tuned high frequency oscillation circuit, a high tension direct current source supplying energy to said circuit through an iron cored choke coil, and a high frequency oscillator energizing said choke at a frequency equal to a fraction of the resonant frequency of the tuned circuit.

Signed at Berlin, Germany, this 27th day of June, 1925.

GEORG VON ARCO.
